UNITED STATES PATENT OFFICE

WALTER A. BATES, OF GARY, INDIANA, ASSIGNOR TO GARY STRUCTURAL STEEL COMPANY, OF GARY, INDIANA, A CORPORATION OF DELAWARE

EXPANDED-METAL STRUCTURE

Application filed June 24, 1926. Serial No. 118,206.

The present invention relates to expanded metal structures.

An object of the present invention is to provide a method for producing expanded metal structures from commercial shapes.

A further object is to provide a method well adapted for commercial operation for treating commercial rolled shapes to produce commercial structures which will have greater strength and will cost less than fabricated structures of the same weight.

A further object is to provide a method of producing expanded metal structures which method will give greater assurance against hidden flaws in the metal than is had in a fabricated structure of the same apparent strength.

Further objects will appear as the description proceeds.

20 Referring to the drawings—

Figure 1 shows in side elevation a commercial rolled shape, an I-beam being chosen for illustration, said commercial rolled shape being provided with transverse slits which illustrate an initial operation in the treatment of said commercial shape according to the present invention;

Figures 2 and 3 are views similar to Figure 1 but showing the rolled shape after subsequent slitting operations have been performed thereon;

Figure 4 is a top plan view of the structure shown in Figures 1 to 3, but after a swedging operation has been performed thereon, and showing a die in position to perform its swedging operation;

Figure 5 is an end view of the structure shown in Figure 4;

Figure 6 is a view in side elevation of a structural steel member in completed form, which structural steel member results from further treatment of the member as shown in Figures 4 and 5; and

Figure 7 is an end view of the structure shown in Figure 6.

As noted above, an I-beam has been chosen for illustrating the present invention, though as the description proceeds it will be apparent that the invention is not limited to I-beams, but is applicable to other forms of

commercial or other shapes. An I-beam of standard design is indicated by the numeral 10, the web 11 of which I-beam is provided with transversely disposed slits 12—12 extending part way across said web, symmetrically of said web, which slits are arranged in pairs, said pairs being preferably equi-spaced along a mid portion of the length of the I-beam. Arranged symmetrically with reference to the pairs of slits 12—12 are other sets of transverse slits 13—13, said slits 13—13 being arranged in sets of four. The outer extremities of the slits 12—12 are preferably disposed along lines 14—14 arranged parallel with the axis of the I-beam 10. The outer extremities of the slits 13—13 are disposed along parallel lines 15—15, which are also substantially parallel with the axis of the I-beam 10. The inner extremities of the slits 13—13 are defined by the lines 14—14. Those slits 13—13 disposed at the two extremities of the slitted portion of the I-beam 10 may be elongated to communicate with each other to form the elongated slits indicated by the numeral 16.

In addition to the transverse slits 12—12 and 13—13, the I-beam is provided with the longitudinally extending slits 17, which slits 17 are disposed along the axis of the I-beam, being disposed in position to connect the mid point of one of the pairs of slits 12 to one of the net adjacent pair of slits 12. The outer extremities of slits 13—13 are connected by longitudinally extending slits 18, said longitudinal slits 18—18 being disposed in position connecting slits of one set of slits 13 to slits of the next adjacent set of slits 13. The slits 18—18 are disposed in overlapping relationship with the slits 17, thereby providing ribbons or lacings which may be swedged from the plane of the web 11 to provide an expanded metal structure.

By reason of the arrangement of slits as above described, a plurality of lacings 19 are provided, separated by portions 20—20, which will be referred to herein as intact, said intact being defined by the slits 12—12.

It will be noted that the outer slits 18—18 are disposed in pairs, their intact 20—20 being directly opposite each other. The in-

tacts between the slits 17—17 are disposed midway between the intacts of said slits 18—18. The slits 13—13 are of substantially half the length of the slits 12—12.

8 The I-beam 10, slotted as above described, is subjected to a swedging operation, a wedge-shaped tool 21 being provided to deform the lacings, as shown in Figures 4 and 5. In practice, the cutting of the slits 18 and the de- 10 forming of the lacings are performed in the same operation, the tool 21 having a width equal to the distance between said slits 18. The semi-completed structure shown in Figures 4 and 5 is then subjected to a pulling or 15 drawing operation, the two flanges of the I-beam being pulled directly away from each other; or, if preferred, pushing force in the direction of the arrows in Figures 4 and 5 may be applied to spread the flanges; or a 20 combination of said pulling and pushing forces may be employed, so long as a resultant component of material value is applied in the original plane of the web 11. The act of separating the two flanges of the I-beam 25 10 will naturally tend to pull the deformed lacings 19—19 back to positions symmetrical with the web of the I-beam. In order to do that, however, said lacings must turn at right angles to said web (that is, at right angles to 30 their original plane), so that the final expanded product will have the shape shown in plan and in cross section in Figures 6 and 7, respectively, the center joint or intact being a U-shaped cross section on the intacts 35 20—20. As appears in Figure 6, the lacings form intersecting diagonals, providing a diamond-shaped conformation.

The structure shown in Figure 6 takes the form of a beam, said structure being illus- 40 trated as having the lower half of its end portions swedged upwardly into engagement with the upper half thereof; this arrangement being advantageous when the structure is to be used as a beam. If preferred, reen- 45 forcing members 22, such as tubing, may be disposed between and preferably welded to the upper and lower portions of the structure. Though Figure 6 illustrates a beam, it will be clear that the invention is equally applicable 50 to columns, diagonals and other structural members.

By reason of the present invention, a method is provided whereby expanded metal structures may be manufactured from commercial 55 rolled shapes, which expanded metal structures will have decided advantages in a commercial sense.

Though one embodiment of the present invention has been chosen for purposes of illustration, it will be understood that many modifications may be made without departing from the scope of the invention. It is intended to cover all such modifications that fall 60 within the scope of the appended claims.

65 What is claimed is—

1. The method of treating a rolled shape having a web which consists of providing said web with openings having substantial dimensions transversely of said web, connecting certain of said transverse open- 70 ings with longitudinal openings to provide lacings attached at both ends to said web, swedging certain of said lacings from the plane of said web by stretching same and applying a force to said rolled shape having a component at right angles to the axis of 75 said rolled shape in a plane substantially coincident with the plane of said web whereby to expand said rolled shape.

2. The method of treating a rolled shape 80 having a web portion which consists in providing said web portion with a plurality of pairs of transverse openings extending only part way across said web and providing said web with other sets of openings disposed transversely of said web, the openings in said sets being disposed outwardly of the lines marking the extremities of the first mentioned openings, slitting said web longitudinally to connect together the outer extremities of certain of said last mentioned openings, slitting said web longitudinally to connect together certain of said first mentioned openings to provide lacings attached at both ends to said web, swedging said 85 lacings normally of said web by stretching same to cause the material defined by said pairs of openings to lie at a relatively great distance from the original plane of said web and applying a force to said rolled shape 90 having a component at right angles to the axis of said rolled shape in a plane substantially coincident with the undeformed portion of said web.

3. The method of treating a rolled shape 105 which consists in providing the web thereof with a plurality of longitudinally extending parallel slits, providing a plurality of transverse openings communicating with the extremities of said longitudinal slits to form 110 lacings attached at both ends to said web, swedging certain of said lacings laterally of said web by stretching same and applying a force to said web in the original plane 115 of said web to return portions of said swedged lacings to the original plane of said web and to turn the remaining portions of said swedged lacings into planes at right angles to the original plane of said web.

4. The method of treating a member hav- 120 ing a flat wall which consists of cutting said flat wall to provide a plurality of sets of apertures spaced along said member, connecting certain of said apertures with longitudinal slits, stretching portions of said wall along said slits from the plane of said wall to provide lacings attached at both ends to said wall and applying a distorting force to said member in the plane of said wall sub- 125 substantially at right angles to said slits to turn 130

said stretched portions through an angle of ninety degrees to positions in which the material thereof is at substantial right angles to the original plane of said wall.

- 5 5. The method of treating a member having a flat wall which consists of cutting said flat wall to provide a plurality of sets of apertures spaced along said wall, connecting certain of said apertures with longitudinal slits stretching portions of said wall in a direction transverse to said wall to form angular strips attached at both ends to said wall and applying a distorting force to said wall in the plane of said wall substantially 70 at right angles to said slits to swing said strips from positions laterally of said wall to positions perpendicular to but symmetrical with the plane of said wall.
- 10 10. The method of treating a member having a flat wall which consists of cutting said flat wall to provide a plurality of spaced slits disposed longitudinally of said member, stretching portions of said wall along said slits from the plane of said wall to provide 75 lacing attached at both ends to said wall and applying a distorting force to said member in the plane of said wall substantially at right angles to said slits to turn said stretched portions through an angle of ninety 80 degrees to positions in which the material thereof is at substantially right angles to the original plane of said wall.

- 85 6. The method of treating a member having a flat wall which consists of cutting said flat wall to provide a plurality of spaced longitudinally extending slits, stretching portions of said wall along said slits from the plane of said wall in a direction transverse to said wall to form angular strips attached at both ends to said wall, and applying a distorting force to said shape in the plane of said wall substantially at right angles to said slits to swing said strips from positions laterally of said wall to positions 90 perpendicular to but symmetrical with the plane of said wall.

- 95 7. The method of treating a member having a flat wall which consists in cutting said flat wall to provide a plurality of sets of apertures spaced along said member, severing and stretching portions of said wall between said sets of apertures to provide lacings attached at their opposite ends to said wall, and applying a distorting force to said member in the plane of said member substantially at right angles to said lacings to turn said stretched portions through an angle of ninety degrees to positions in which the material thereof is at substantially right angles to the 100 original plane of said wall.

- 110 8. The method of treating a member having a flat wall which consists of cutting said flat wall to provide a plurality of sets of apertures spaced along said wall, severing and stretching portions of said wall between 115

said apertures to provide lacings attached at both of their ends to said wall, said stretching being accomplished in a direction transverse to said wall to form angular strips, and applying a distorting force to said wall in the plane of said wall substantially at right angles to said strips to swing said strips from positions laterally of said wall to positions perpendicular to but symmetrical with the plane of said wall.

Signed at Chicago, Illinois, this 9th day 75 of June, 1926.
